UNITED STATES PATENT OFFICE

ALFRED M. HARRIS, OF WASHINGTON, DISTRICT OF COLUMBIA, ASSIGNEE TO DAVID FRANKLIN COOK, OF CHEYENNE, WYOMING

INTERNAL COMBUSTION ENGINE

Application filed December 30, 1929. Serial No. 417,487.

This invention relates to improvements in internal combustion engines of the four cycle type.

The primary object of this invention is to provide a sliding arrangement of the cylinders of the engine relative to the crank case whereby the combustion chamber may be varied in size.

A further object of this invention is to provide an engine of the above mentioned character adapted to increase the expansion of burned gases over the entire scale of the number of revolutions per minute to which the engine is subjected.

A still further object of this invention is to provide means adapted to be operated mechanically, manually or automatically for moving the cylinders relative to the crank case.

A still further object of this invention is to provide a novel form of engine in which the cylinders may be moved relative to the crank case to increase or decrease the size of the combustion chamber to produce a low or high speed engine and simultaneously change the clearance in the valve gear push rods accordingly.

A still further object of this invention is to provide an internal combustion engine of the above mentioned character adapted to develop more horse power out of a smaller amount of fuel and whereby the engine will be balanced at all times irrespective of the distance the cylinders are moved on the crank case.

Heretofore it has been common practice to vary the size of the combustion chamber of an internal combustion engine by raising or lowering the cylinder head relative to the cylinder and to regulate the throw of the crankshaft relative to the cylinder block by employing gears associated with the crankshaft. This practice is objectionable due to the disadvantages in arrangement of the valve gearing, timing mechanism, and other parts of the engine which are necessary for the efficient and complete operation of the engine.

The above disadvantages are overcome by providing an engine having a stationary

crank case with cylinder blocks attached thereto adapted to slide laterally whereby the cylinder blocks are moved in a horizontal plane to increase or decrease the combustion chamber and simultaneously move the valve gear push rods to increase or decrease the clearance between the valve stems and rocker arms in accordance with the high or low speed of the engine.

Other objects and advantages of the invention will become apparent during the course of the following description forming a part of this specification and in which,

Figure 1 is a fragmentary plan view of the engine embodying this invention showing a pair of cylinder blocks slidably secured to the crank case and the means at the opposite ends of the cylinder blocks for moving the same towards and away from each other.

Figure 2 is an end elevational view of the invention showing the pair of cylinder blocks and the oppositely screw threaded rod for moving the blocks laterally on the crank case.

Figure 3 is an enlarged fragmentary side elevational view of the engine showing more in detail the construction and arrangement of the cylinder block operating mechanism.

Figure 4 is a fragmentary cross sectional view through one of the hold down devices showing the same passing through a slot in the cylinder block flange and secured to the crank case, and

Figure 5 is an enlarged transverse cross sectional view of the engine embodying this invention showing the movable cylinder blocks secured to the crank case, the arrangement of the pistons and connecting rods relative to the crank shaft and the novel arrangement of the valve gearing.

For a more detailed description of the invention, attention is directed to the drawings wherein the reference character 5 will generally be referred to as the crank case, formed in the usual manner comprising sections 6 and 7 having flanges held together by bolts 8.

Longitudinally disposed in the crank case 5 is a crank shaft 9 of a conventional form having wrists 10 arranged in a manner suitable for an eight cylinder motor wherein four cylinders are mounted in parallel relation.

Journal bearings are provided for the ends of the crank shaft in the end walls of the crank case in the usual manner.

Slidably bolted to overturned edges 11 of the crank case section 6 is a pair of parallel cylinder blocks 12 having water spaces 13 and closed at their upper ends by a cylinder head 14. Intake and exhaust valves 15 according to the desired construction of the engine are mounted in openings in the cylinder blocks and each valve is provided with a stem 16, adapted to be guided in the head as at 17. Intake and exhaust ports 18 communicate with the valve openings to accomplish the inlet and exhaust of gases in the usual manner.

The lowermost portion of each cylinder block 12 is provided with a laterally extending flange 19 which extends around the entire lower end of the cylinder blocks 12 whereby the flanges 19 will set upon the overturned edges of the crank case 11. It will be noted that the adjacent flanges 19 of the cylinder blocks are seated upon a longitudinal strip 20 which connects with the end walls of the crank case section 6. It may be found in practice to form the upper wall of the crank case section 6 of a single piece of metal having oval shaped opening for communication with the cylinder. A suitable oil retaining packing 21 may be carried by the cylinder flanges 19 to engage the upper face of the crank case flange 11 to prevent oil from leaking past the connection between the crank case and cylinder. Openings 22 are adapted to communicate with oil grooves 23 extending around each of the cylinder blocks.

Each of the cylinder blocks 12 are secured to the crank case section 6 in a slidable fashion as by means of a series of bolts 24 being passed through openings 25 in the flanges 11 and through slotted openings 26 in the flanges 19 which communicate with each other. The bolts 24 are held in place by being provided with any suitable type of automatic release nut 27 threaded on the bolt and having an annular lower flange 28 for covering the elongated slot 26 to further prevent the escape of oil.

Pistons 30 are reciprocably mounted in the respective cylinders of the cylinder blocks and are connected to the wrists 10 of the crank shaft by offset connecting rods 31 having an angle portion 32 in order to allow the lower end 33 to be presented to the crank shaft at the right angle.

A series of valve tappets 34 are arranged longitudinally in the plate 20 of the crank case section 6 and are adapted to be reciprocated by cams 35 secured to the cam shaft 36. Each of the tappet plungers 34 is provided with a spherical socket to receive the lower ends of the push rods 37, while the upper ends of the push rods engage rocker shafts 38 pivoted as at 39 to the supports 40. The

opposite ends of the rocker shafts operate upon the valve stems 16 and as shown in Figure 5, an adjustment screw 41 is held in close relation to the valve stem 16 for the purpose of the necessary adjustments. It is to be understood that the usual springs 42 are mounted on the valve stems 16 for normally holding the valves 15 in their closed position.

As shown in the several figures of the drawings, the cylinder blocks 12 are provided at each end with a cast lug 43 having a transverse screw threaded opening for receiving corresponding screw threads 44 which are in opposed relation on the rods 45, whereby rotation of the screw threaded rods 45 will cause the cylinder blocks 12 to be moved towards or away from one another to vary the combustion chamber. A pair of cast lugs 46 are also formed on the ends of the crank case section 6 rotatably supporting the oppositely screw threaded rods 45.

Mounted between the lugs 45 rigidly secured to the screw threaded rods 45 are worm wheels 47 adapted to mesh with worm gears 48 secured to the opposite ends of the longitudinal shaft 49. Rotation of the shaft 49 causes the worm wheels 47 at each end of the cylinder blocks to rotate the screw threaded rods 45 whereby the cylinder blocks 12 will be moved towards or away from each other as desired.

Mechanical means may be provided for rotating the shaft 49 such as a governor associated with the crank shaft or thermostatic means may be employed for rotating the shaft 49 or a hand wheel may be provided on the shaft 49 for operating the same manually if so desired.

A cover 50 is placed over the overhead valve gearing to protect the same from dirt and prevent the loss of the oil fed to the rocker arms.

It is to be understood that the form of invention shown in the drawings is to be taken as a preferred example of the same and that the invention may be employed in connection with motors of the radial type, opposed type, and the vertical type. It is also to be understood that various forms of valve gearing employing push rods may be employed although the form shown and described is the preferred form.

Having described the invention, I claim:

1. An internal combustion engine, comprising a crank case, cylinders movably mounted on the crank case, pistons and valve gearing for the cylinders and means for moving the cylinders laterally relative to the crank case.

2. An engine having a crank case and a cylinder block mounted thereon, the block being free to assume a plurality of positions with respect to the crank case, the plane containing the axis of said cylinders in one position of said block being parallel with the

plane containing said axis in any other position assumed thereby.

3. An engine having a crank case and a cylinder block, relative movement between the block and crank case, means interposed between the crank case and the cylinder block for sealing the continuously moving faces on the complementary faces thereof, and means for moving the block laterally relative to the crank case.

4. An engine comprising a crank case and a pair of cylinder blocks thereon, said blocks being relative movable toward and away from each other on the crank case and means for moving the cylinder blocks simultaneously in opposite directions.

5. An engine comprising a crank case and a pair of cylinder blocks thereon, said blocks being movable on the crank case and means for moving the cylinder blocks simultaneously in opposite directions.

6. An engine comprising a crank case, a pair of cylinder blocks movably mounted on the crank case, sealing means interposed between the cylinder blocks and crank case, and means for moving the cylinder blocks on the crank case simultaneously in opposite directions.

7. An engine comprising a crank case, a cylinder block slidably mounted on the crank case and means for moving the cylinder block relative to the crank case.

8. An engine comprising a crank case, a cylinder block and valve gearing, said cylinder block being slidably mounted on the crank case and means for moving the cylinder block relative to the crank case simultaneously affecting a change in the valve gearing clearance.

9. An engine comprising a crank case, two or more cylinder blocks movably mounted on the crank case, valve gearing associated with the cylinder block, and means for sliding the cylinder block laterally on the crank case, said means also effecting an adjustment in the valve gearing to increase or decrease the clearance.

10. An engine comprising a crank case, a pair of cylinder blocks mounted on the crank case extending parallel with each other, said blocks being capable of a sliding movement relative to the crank case, and means for moving the cylinder blocks toward and away from each other, each block moving the same distance as the other.

11. An engine comprising a crank case, a pair of cylinder blocks movably mounted on the crank case, valve gearing associated with the engine, means for moving the cylinder blocks on the crank case in simultaneously opposite directions and means operable by the first named means for effecting an adjustment of the valve gearing.

In testimony whereof I affix my signature.

ALFRED M. HARRIS.
